DES. 2102

Fredrick Stearns, of Detroit, Mich.

Letter Patent No. 3102. Dated June 20, 1865

Design for a Trade Mark.

The Schedule referred to in the Letter Patent and making part of the same.

To all whom it may concern.

Be it known that Fredrick P. Stearns, of the City of Detroit, County of Wayne, and State of Michigan, have invented or produced a Design for a Trade Mark Label, to be engraved and printed as a Label on Wrappers, Circulars, Posters, Labels etc, the design for a Label for Amber Oil consisting of the words "Stearns Amber Oil for renewing, beautifying and dressing the Hair. Stearns Druggist and Perfumer Detroit" arranged and ornamented as shown in the drawings accompanying this application and forming a part thereof.

That I claim is the Design for a "Trade Mark Label" as shown and described.
